(57) **CLAIM**

The ornamental design for gene amplification chips for medical and laboratory use, as shown and described.

DESCRIPTION

1.-2. Gene amplification chip for medical and laboratory use

1.1 : Front

1.2 : Enlarged cross-sectional view

1.3 : Enlarged cross-sectional view

1.4 : Cross sectional

2.10 : Right

2.11 : Left

The dashed broken lines depict portions of the gene amplification chip that form no part of the claimed design; the dot-dashed broken lines represent boundaries of the claimed gene amplification chip and form no part of the claimed design.

The article of this design is transparent. Design 1: reproduction **1.2** is an enlarged cross-sectional view sectioned vertically at a left part outside the left reaction channel of reproduction **1.1**, reproduction **1.3** is an enlarged cross-sectional view sectioned vertically at the center of the right reaction channel of reproduction **1.1**, reproduction **1.4** is a cross-sectional view sectioned horizontally along the detection channel of reproduction **1.1**, and reproduction **1.5** is a cross-sectional view sectioned horizontally at a top part of the claimed portion of reproduction **1.1**; design 2: reproduction **2.2** is an enlarged cross-sectional view sectioned vertically at the center of the detection channel of reproduction **2.1**, reproduction **2.3** is an enlarged cross-sectional view sectioned vertically at a left part outside the left reaction channel of reproduction **2.1**, reproduction **2.4** is a cross-sectional view sectioned horizontally along the detection channel of reproduction **2.1**, and reproduction **2.5** is a cross-sectional view sectioned horizontally at a top part of the claimed portion of reproduction **2.1**.
